UNITED STATES PATENT OFFICE.

JAMES R. CONNELL, OF PORTSMOUTH, NEW HAMPSHIRE.

TRACE-LOCK.

SPECIFICATION forming part of Letters Patent No. 252,019, dated January 10, 1882.

Application filed November 7, 1881. (No model.)

To all whom it may concern:

Be it known that I, JAMES R. CONNELL, a citizen of the United States, residing at Portsmouth, in the county of Rockingham and State 5 of New Hampshire, have invented new and useful Improvements in Trace-Locks, of which the following is a specification.

This invention relates to the details of the construction of improved trace-locks pivoted to 10 the end of the trace-bar, the object being to provide a lock for this purpose which permits of attaching the trace to the whiffletree with great facility, and which affords perfect security against any danger from accidental unfastening of the trace.

In the drawings forming part of this specification, Figure 1 is a plan view of a whiffletree having thereon trace-locks constructed according to my invention. Fig. 2 is a plan view 20 of the interior of the lock-case, showing the spring and the end of the trace-bar, the latter partly in section. Fig. 3 is a perspective view of one end of the whiffletree having the lock thereon, the bottom plate being partly removed from the latter and the end of the trace-bar shown in dotted lines. Fig. 4 is a perspective view of the end of the trace-bar. Fig. 5 is a view of one end of the whiffletree, showing a transverse section of the trace-lock. Fig. 30 6 is a perspective view of the lock-spring.

In the drawings, B is the whiffletree. a is the trace-bar. b is the trace-lock. e is the trace-lock case. c is the trace-lock bottom plate. i are steady-pins on case e. o is the lock-spring. 35 v are turned-down corners on plate c.

My improved trace-lock consists of the case e, of an oval form and concavo-convex in cross-section, to the inner face of which are secured the steady-pins i of the spring o, whose four 40 ends are bent downward to make its center stand up away from the inner face of case e, when placed therein in the position shown in Figs. 2 and 3, and of the bottom plate, c, which is of like form to case e, and is secured thereto, 45 as shown, said plate c being cut to form a slot from one edge inward, and the sides of said slot bent toward the interior of case e to form the corners v opposite to the steady-pins i.

The above-named parts—that is to say, the 50 case, spring, and bottom plate—co-operate with the T-shaped trace-bar a to complete the

trace-lock, as follows: Said trace-bar is secured by one end to the end of the whiffletree B in the usual manner, and in cross-section, near its end, is of the form shown in Fig. 2 at the line 55 x x, Fig. 5, and is provided at its extremity with a cross-bar, n.

In practice I employ the case e, constructed, as shown in Fig. 3, with two steady-pins, i, therein, and when thus made the parts of the 60 lock are united with and upon the end of the trace-bar, as follows: Into said case e is placed the spring o, with one edge of its long arms against the pins i and its short arms extending toward the sides of the case. Thus placed, 65 its central portion is highest, and may have a spring motion toward the case under it. The end of the trace-bar a is next placed upon spring o, with one side of the cross-bar n next to the steady-pins i, and over the extended 70 ends of said cross-bar n, and astride of bar a, is next placed the slotted bottom plate, c, and it is there secured to the rim of case e, or to the pins i, or to both. The turned-down corners 75 v on said plate c, when the latter is placed on case e, as above described, stand opposite to the pins i, and the latter, together with the corners v, constitute abutments on each side of the cross-bar n, to hold the latter and case e in proper relative positions and to keep spring 80 o properly under the end of bar a.

In Fig. 2 are shown the pins i, set on each side of the cross-bar n. This construction may be adopted whenever it is thought preferable to employ said pins instead of the turned-down 85 corners v on plate c for abutments to said cross-bar.

When the above-described parts of the trace-lock and trace-bar have been assembled, as set forth, it will be found that upon attempting to turn the lock b over, so that its faces are on a line, or nearly so, with bar a, spring o, bearing against the end of said bar, will act to retain the lock in the position shown at the left in Fig. 1; but when it has been turned over 90 to the position shown at the right in said figure said spring will have been carried from the end of bar a over against the side of the latter and of cross bar n, and the lock b will thereby be retained in the last-named position, which 95 is the one which permits of passing the trace over it easily onto the bar a, and when the 100

trace is thereon and the lock has been turned back, as at the left in Fig. 1, spring *o* retains it in that position and effectually secures the trace to the whiffletree.

5 What I claim as my invention is—

In combination, the case *e*, having the steady-pins *i* therein, the spring *o*, the slotted bottom

plate, *c*, having the abutments *v* thereon, and the trace-bar *a*, provided with the cross-bar *n*, substantially as and for the purpose set forth. *to*

JAMES R. CONNELL.
